VENDING MACHINE

James F. Hoover, Duncan, Okla.

Application December 4, 1931. Serial No. 579,052

6 Claims. (Cl. 226—49)

My invention relates to vending machines, and more particularly to a machine for vending packaged peanuts.

The invention consists in the provision of a vending machine having means for maintaining the peanuts or the like in a warm tasteful state, together with means for measuring the amount to be vended in addition to means for automatically packing the measured quantity and subsequently delivering the package of peanuts through a part of the machine to be withdrawn therefrom in a manner convenient to the purchaser.

The invention, together with its numerous objects and advantages will be best understood from a study of the following description, taken in connection with the accompanying drawings wherein is illustrated the preferred embodiment of the invention, it being distinctly understood that my invention is in nowise to be limited to the specific embodiment shown, the invention being restricted only by the requirement of the prior art and the scope of the appended claims.

Referring to the drawings:

Figure 1 is an elevational view of one side of the invention.

Figure 2 is a similar view of a relatively opposite side thereof.

Figure 3 is a vertical transverse sectional elevational view therethrough.

Figure 4 is a fragmentary longitudinal sectional elevational view through certain parts of the device to be hereinafter more fully referred to, and showing the position of the chute and the measuring device just prior to a discharge of the article or articles being vended.

Figure 5 is a view similar to Figure 4 showing the bag to receive the charge being in a fully opened position.

Figure 6 is an elevational view of one side of the chute showing the parts thereof in one position relative to one another.

Figure 7 is a view similar to Figure 6, viewing the chute from a relatively opposite side thereof and showing the parts of the chute in a second position relative to one another.

Figure 8 is a vertical transverse sectional view taken substantially on the line 8—8 of Figure 6.

Figure 9 is a side elevational view of one end portion of the chute.

Figure 10 is a perspective view of a pivoted sack clamp.

Figure 11 is a plan view of a cam member certain parts being broken away and shown in section.

Figure 12 is a perspective view of a bag opening or expanding member.

Figure 13 is a vertical sectional view through the rotatable combined valve and measuring member.

Figure 14 is a side elevational view of a drum for supporting the member shown in Figure 13.

Figure 15 is a horizontal longitudinal sectional view through a sack holder.

Figure 16 is a perspective view of a latch bar for locking the bag holder in a predetermined position.

Figure 17 is a longitudinal edge elevational view of a bag or sack.

In actual practice, it is to be understood that a suitable casing would be provided for housing the mechanism forming the essence of the present invention, such housing in the present instance being omitted as unessential to a sufficient understanding of the invention.

Within such a housing would be placed a skeleton frame structure such as suggested in the drawings and designated generally by the reference character 1.

In this manner suitable supporting and bracing structure is provided for a drum 2 which, as clearly suggested in Figure 14, is open at relatively opposite ends thereof, and in the periphery thereof is provided with a discharge opening 3 together with, as best shown in Figure 4, an opening 4 about which is a flared mouth 5 projecting substantially radial to the drum as shown in the last mentioned figure. The mouth 5 conformably receives the lower end of a removable hopper 6 into which the peanuts or the like to be vended are initially placed.

Opening 4 is controlled by a combined valve and measuring cylinder 7 that is provided in its periphery with an intake and discharge orifice 8 provided for an article receiving pocket 9 which may be of any desired predetermined capacity.

Drum 2 at the lower end of opening 3 is provided with opposed ears 10 supporting a hinge pin 11 that is normally rotated in one direction through the medium of a spring 12. A chute section 13 is connected with the hinge pin 11 and is provided with opposed sides 13a provided adjacent the pivoted end of the section with concaved edges 13b. (See Figures 6 and 7.)

A sliding chute section 14 is also provided and has relatively long narrow sides 15 at one end straddling the chute section 13. Sides 15 are longitudinally slotted as at 16 for accommodating lateral lugs 17 projecting from the sides 13a whereby the sliding section 14 is constrained to

slide substantially in its own plane for extending or retracting the extensible chute formed by the sections 13, 14. Chute section 14 is normally retained in its retracted position, that is in the 5 position shown in Figure 3 through the medium of springs 18 suitably anchored at one end to the skeleton frame 1, and at their other ends respectively secured to the upper ends of arms 19 fixed to the sides 15 of the section 14 intermediate the ends of such sides.

Corresponding ends of the sides 15 are provided with heads 20 arranged in the path of cams 21 provided on relatively opposite ends of the cylinder 7 (see Figure 2), the cams being of 15 any suitable shape and construction, but preferably of the shape and construction suggested in Figure 11.

It is therefore apparent, that when the drum 7 rotates in one direction the cams 21 will engage the heads 20 to shift them from the position shown in Figure 6 to the position shown in Figure 7 whereby tray section 14 is projected beyond tray section 13 and the tray or chute formed by such sections is then in a fully extended position.

As will be apparent from a study of Figures 4 and 5, as the cams 21 move out of engagement with the head 20, the convex faces of the cams move into engagement with the concave edges 30 13b causing rotation of chute section 13 so that the chute in its extended position swings downwardly from the position shown in Figure 4 to the position shown in Figure 5.

Forming part of the skeleton frame structure 1 35 is a pair of inclined oppositely disposed relatively spaced supporting bars 1a which slidably support therebetween a bag holder, the latter comprising side walls 23, and end wall 24; each of said walls on its lower edge being provided with an inwardly directed flange 25. At their free 40 ends and adjacent their lower edges the walls 23 are connected by a bar 26 that is inclined at an angle to the perpendicular and is curved in transverse cross section. The holder referred to is adapted to accommodate a stack of expandable bags or sacks 27 supported on the flanges 25.

A suitable hand weight may be employed for compressing the stack, being arranged on the up- 45 permost sack or bag as suggested in Figures 4 and 5. Each bag or sack 27 at the mouth thereof has opposed walls terminating one inwardly of the other so that the free end of the longer wall is supported by the bar 26 and the free end of the shorter wall is normally disposed below the 55 plane of the bar 26 whereby to facilitate insertion of a bag expanding member designated generally by the reference character 29.

As shown in Figure 12 the bag expander 29 is 60 preferably formed from a single length of wire bent into a substantial U and at the open end of the U, opposed sides 30 of the bag expander are directed laterally in opposite directions as at 31 and the extensions 31 merge into return extensions having angular portions thus forming 65 angular depending arms 32. The expander 29 is pivotally supported on the longitudinally extensible chute in the following manner: The extensions 31 extend through apertures provided in the arms 19 adjacent the fixed ends of the arms so that the arms 32 of the expander normally extend downwardly below the plane of the chute. Adjacent the bar 26, the skeleton frame bars 1a have depending therefrom and arranged at a suitable angle to the perpendicular, bars 1b 75 which at their lower ends are provided with

lateral pins 33 arranged in the path of the arms 32.

From the foregoing it will be apparent that with the chute in its retracted position, the expander 29 is normally disposed parallel to the chute as suggested in Figure 3. As the chute is extended in the manner hereinbefore explained, the closed end of the U-shaped body of the expander together with the proximate end of the chute section 14 will pass into the bag through the mouth thereof, and as the chute is swung downwardly from the position shown in Figure 4 to the position shown in Figure 5 in a manner hereinbefore also fully explained, the bag 27 so engaged will be displaced and move with the chute.

This downward movement of the chute will cause the arms 32 of the expander to engage the pins 33 rotating the expander to the position shown in Figure 5 whereupon the displaced bag 27 will be expanded as shown in the last mentioned figure, the bag being now in position to receive the contents of the pocket 9.

A bag clamping bar 34 is provided (Fig. 10) and adjacent one end thereof of the bar is equipped as at 35 for pivotal engagement with the hinge pin 11, and at said end is provided with a depending lug 36 having suitably secured thereto and extending laterally from relatively opposite sides thereof a pin 37 that is engaged by the depending ends of heads 20 when the latter have moved into the position shown in Figure 4. Bag clamping bar 34 being normally in the position shown in Figure 3, it will be apparent that this engagement of the heads 20 with the pin 37 will cause the bar 34 to swing upwardly to the position suggested in Figure 4 in suitably timed relation with respect to the sliding movement of the tray 14 whereby to clamp a proximate wall of the bag 27 between the bar 34 and the tray 14 as suggested in Figures 4 and 5. As therein shown to advantage, bar 34 adjacent its free end is provided with a head or protuberance 38 which engages said proximate wall of the bag 27 and forces a portion of said wall upwardly through an aperture 39 provided in the sliding tray section 14.

With the parts as shown in Figure 5, it will be apparent that the contents of the pocket 9 will pass therefrom on to the tray and from the tray into the expanded bag 27. As cams 21 move out of engagement with the edges 13b of the tray 14 sides 13s the tray section 13 will begin to rotate in a reverse direction that is to say will again swing upwardly from the position shown in Figure 5 to the position shown in Figure 4 and at the same time under action of springs 18, tray 14 will begin to move inwardly to the position suggested in Figure 3.

Also, pressure of the heads 20 against the pin 37 is being released leaving the bar 34 free to swing to its normal position or to the position shown in Figure 3 whereupon the bag 27 together with its contents, will move longitudinally with respect to the chute and fall by gravity on to a pivoted tray 40 pivoted at one end as at 41 in the lower portion of the skeleton frame 1. The tray 40 adjacent its free end is provided with a guide plate 42 whereby when the tray 40 is in its lowermost or dotted line position shown in Figure 3 the bag together with its contents will be presented at the forward end of the tray to be easily removed therefrom by the purchaser.

Tray 40 is normally urged upwardly to the position suggested by full lines in Figure 3 through the medium of spring means 43 suitably anchored to the skeleton frame 1 and connected with arms

150

or extensions 44 provided adjacent the pivoted end of the tray and extending toward the free end of the tray at a suitable angle relative to the tray. Downward swinging movement of the tray 5 is limited by a transverse roller 45.

From a study of Figure 3, it will be seen that with the parts all in their normal positions, the chute is limited in its upward swinging movement, by reason of the fact that the forward free 10 end of the chute section 14 normally abuts the cross bar 26 of the sack holder.

The bag holder is releasably retained in operative position with respect to the chute through the medium of a latch bar 46 which at its end is 15 provided with apertured lugs pivotally engaged as at 47 with horizontal bars 1c of the skeleton frame. Bar 46 intermediate its ends is provided with a keeper lug 48 disposed transversely and having a beveled end engaging a proximate edge 20 of an upper cross bar 23a extending between the walls 23 of the bag holder as clearly suggested in Figure 3. A suitable lever or handle 49 is provided at one end of the bar 46 to facilitate moving of the bar about its pivot into and out of 25 operative engagement with the bar 23a.

A member 50 is also suitably mounted within the skeleton frame 1 and has bearing contact with an upper transverse bar 24a provided adjacent the rear wall 24 of the bag holder and 30 curved to maintain the bottom portion of the bag holder in bearing contact with the inclined frame bars 1a.

It is apparent, that when the bag holder is removed for the purpose of replenishing the supply of sacks 27 the chute under action of spring 35 18 will have a tendency to swing upwardly. To prevent this, there is provided a stop rod 52 that is somewhat angular, and which at its upper end is pivoted as at 53 to one of the frame bars 1c 40 and at said pivoted end is provided with a lateral projection 52a the terminal of which is normally urged into bearing contact with the upper edge of an adjacent side 13a through the medium of a spring 54 connected at one end with the extension 45 52a and at a relatively opposite end anchored to a frame bar 1a. (See Figure 3.)

The rod 52 below the pivot 53 is also provided with a finger 55 arranged in the path of the bag holder and adapted to be engaged with the forward 50 edge of an adjacent side wall 23 of the holder when the latter is moved into its final operative position with respect to the chute whereby to swing the rod toward the right in Figure 1 permitting the chute to swing upwardly 55 a sufficient distance to permit the forward edge of the chute section 14 to engage the under side or face of the cross bar 26.

For driving the cylinder 7 there is suitably mounted on one side of the skeleton frame 1 an 60 electric motor 56 that has driving connections with the drum through the medium of gearing 57. (See Figure 2.)

On a relatively opposite side of the drum 7 there is provided a gear 58 in mesh with a suitably mounted gear 59 and on the pivot 60 provided 65 for the gear 59 there is mounted for rotation relative thereto an arm 61 which adjacent its pivoted end is engaged with a suitably anchored spring 62. Arm 61 is adapted to be swung about 70 its pivot 60 against the action of spring 62 through the medium of an eccentric pin 63 provided on the gear 69 and arranged to engage the arm 61. While the arm 61 is completing a full revolution the free end of the arm is adapted to 75 engage the toothed edge of a ratchet wheel 64

arranged to rotate about a fixed pivot 65 and normally urged in one direction namely in a clockwise direction through the medium of suitable spring means (not shown) and arranged in a housing 66. This referred to engagement of arm 80 61 with wheel 64 will cause the same to rotate in an anti-clockwise direction a distance of one ratchet tooth.

Clockwise rotation of the ratchet wheel 64 is normally retarded through the medium of a suitably mounted pivoted dog 67 one end of which is normally engaged with the teeth of the ratchet wheel through the medium of a spring 68. The free end of dog 67 is normally arranged in operative position to the lower or discharge end of an inclined coin chute 68 into which a coin is fed from a suitably mounted and well known type of coin receiving tray and shifter device 69. Since the particular structure 69 is well known in the art and is not of the essence of the present invention 90 a detail description thereof is deemed unnecessary.

From the foregoing it will be apparent that a coin discharging from the chute 68 will engage that end of the dog 67 arranged in the path of the 100 coin whereby the dog 67 will be rocked against the action of spring 68 and will remain out of engagement with the ratchet wheel 64 a period of time sufficient to permit the ratchet wheel to rotate in a clockwise direction the distance of one ratchet 105 tooth.

This partial rotation of ratchet wheel 64 permits of the closing of a suitably mounted switch controlling the circuit to the motor 56. The switch referred to includes a relatively fixed spring 110 contact 70 and a relatively movable contact 71 provided at one end of a pivotally mounted dog 72 of insulating material. The end of the dog 72 remote from the contact 71 is arranged in the path of an eccentric pin 74 provided on the ratchet 115 wheel 64. Dog 72 is normally urged to rotate in one direction for engaging contact 71 with contact 70 through the medium of a suitably anchored spring 75.

Normally eccentric pin 74 is engaged with the 120 proximate end of the dog 72 so that the circuit to the motor 56 is normally open. Manifestly, upon the insertion of a coin into the machine, and the subsequent engagement thereof with the dog 67 pin 74 will be moved out of engagement with 125 dog 72 and the latter under action of spring 75 will rotate so as to engage contacts 71, 72 thus closing the circuit to the motor. Rotation of the drum will, through the medium of gear 58 meshing with gear 59 rotate the latter one complete 130 revolution and pin 63 engaging arm 61 will cause the same to rotate about its pivot and during such rotation to engage the periphery of the ratchet wheel 64 causing the latter to rotate in a reverse direction, that is in an anti-clockwise direction 135 the distance of one tooth so that pin 74 will engage the proximate end of the dog 72 rotating the latter toward the right in Figure 1 thus separating contact 71, 70 for opening the circuit to the motor and thus stop rotation of cylinder 7.

It is thought apparent, that for each coin placed in the machine, the ratchet wheel 64 will be rotated the distance of one tooth with the result that the circuit to the motor would remain closed until a reverse direction of rotation on the part 145 of the ratchet wheel 64 has been made the required number of teeth to move the pin 74 into engagement with the dog 72. In order therefore to open the circuit at the completion of each discharge of the pocket 9 means is provided for 150

separating the contacts 70 and 71 upon the swinging of the tray 40 to the dotted line position shown in Figure 3. Such means comprises a rod 77 pivotally connected at one end to an arm 78 provided on the pivot rod 41 of the tray 40.

The rod 77 is constrained to reciprocate vertically and at its upper end is arranged in the path of the dog 72, so that as shown in Figure 1, with the contacts 70 and 71 in engagement, a downward 10 swinging movement of the tray 40 to the dotted line position in Figure 3 would cause an upward movement of the rod 77, and the upper end of the rod will engage the dog 72 swinging the same about its pivot against the action of spring 75 15 thus separating the contacts 70, 71 and opening the circuit to the motor.

When a sack of peanuts or the like is removed from the lowered tray, the latter will under action of spring 43 swing to the full line position 20 shown in Figures 1 and 3 thus causing rod 77 to move downwardly, and dog 72 under action of spring 75 will rotate to reengage contacts 70 and 71 to close the circuit. Thus a desired number of coins, within reason may be placed one 25 immediately following the other within the device and sacked peanuts or the like will be delivered one after another to the purchaser without any further operation on the part of the purchaser.

30 Suitable means may be provided for maintaining the salted peanuts or like articles to be vended in a warm tasteful state, and in the present instance such means consists in properly positioned electric heating elements 79, the latter in the present instance being electric bulbs which have been found effective for this purpose.

It is also to be understood that a suitable tray 35 will be provided for receiving the coins discharging from the chute 58. (See Figure 1.)

The operation of the device is thought apparent from the foregoing and may be briefly summarized as follows: The salted peanuts or other articles to be vended are placed within the 45 hopper 6 and by gravity pass into the pocket 9 when the opening 8 of the cylinder 7 passes across the opening 4 provided on the periphery of the casing 2. The capacity of the pocket 9 is substantially the same as the capacity of a 50 sack 27. Upon an insertion of the coin of the proper denomination the dog 57 is actuated in the manner hereinbefore described whereupon the ratchet wheel 64 is rotated the distance of one ratchet tooth with the result that the contacts 70 and 71 are moved into engagement thus closing the circuit to the motor 56 causing the cylinder 7 to revolve.

As the cylinder 7 rotates the cams 21 thereon come into contact first with the heads 20 resulting in a projection of the tray section 14 and the projecting tray section 14 together with the bag expander 29 pass into the mouth of the lowermost sack 27. The cams 21 next come into contact with the edges 13b of the chute sides 13 causing the extended chute to swing downwardly to the position shown in Figure 5 thus displacing the lowermost bag 27, and the expander 29 being rocked about its pivot by reason of the arms 32 of the expander engaging the pin 33, the bag 27 with the chute in the position shown in Figure 5 will be expanded.

With the bag in this expanded position it will be seen that opening 8 is now in registry with the opening 3 in the drum or casing 2 as shown in Figure 5 so that the contents of the pocket 9

will by gravity discharge therefrom and by reason of the extended chute be directed into the expanded bag 27 which is releasably held in expanded position at the lower end of the chute by reason of the clamping bar 34 having been 80 swung upwardly into cooperative clamping relation with the chute section 14. This upward swinging movement of the bar 34 is accomplished, as before explained, by reason of the lower ends of the heads 20 engaging the pin 37 when the 85 chute has been longitudinally extended.

As the cams 21 move out of engagement with the edges 13b, heads 20 being free of engagement of the cams bar 34 swings to its normal position, chute section 14 returns under action of springs 90 18 to its normal position and the sack 27 with its contents is released and falls on to the tray 40. During this revolving of the drum the gear 59 also revolves and the pin 63 thereof engaging the arm 61 carries the same with the gear 59 95 and at the completion of the discharge from pocket 9 and the movement of the drum to cause the opening 8 thereof to pass out of registry with the opening 3 ratchet wheel 64 will, by reason of arm 61 engaging the periphery thereof rotates in a reverse or counter clockwise direction whereupon pin 74 is again engaged with the dog 72 to actuate the latter for separating the contacts 70 and 71 thus opening the circuit to the motor completing the cycle of operation.

Even though I have herein shown and described the preferred embodiment of the invention, it is to be understood that I in no wise intend to limit myself to the particular details of construction, combination and arrangement of 110 parts, beyond the requirement of the prior art and scope of the appended claims.

Having thus described my invention, what I claim as new is:

1. In a device of the character described, and in combination, a charge measuring device including a rotatable part, a longitudinally extensible chute pivotally mounted to receive a charge from said measuring device, means for supporting a bag in a substantially closed position, and in operative position with respect to said chute, a pivotally mounted bag clamping member cooperable with said chute for engaging the bag to yieldably retain the latter in position to receive a charge from said chute, a pivoted bag expanding member cooperable with the chute for expanding the bag, driving means for the charge measuring member, means for extending said chute upon rotation of said charge measuring member, said last mentioned means including 120 means for moving the bag clamping member into the bag clamping position with respect to said chute, means for causing the bag expanding member to rotate relative to the chute during rotation of the latter and yieldable means for retracting said chute.

2. In a device of the character described in combination, a charge measuring rotatably mounted cylinder, a pivotally mounted chute arranged to receive a charge from said cylinder, means for supporting a substantially normally closed sack in substantial alignment with said chute, said chute being longitudinally extensible and having its free end arranged for insertion into the bag, means for rotating said cylinder, means for transmitting movement of the cylinder to the chute, and for extending the chute longitudinally, means cooperating with the chute for expanding the bag subsequent to a displacement of the bag and means for releasably retaining the 130

- bag in expanded condition to receive a charge from said cylinder, means for arresting the transmission of power to said cylinder at the completion of each full revolution of the cylinder, and 5 yieldable means normally retaining the chute in a contracted condition.
3. In a device of the character described, in combination, a pivotally mounted normally contracted longitudinally extensible chute, means for 10 emitting a discharge on to said chute, a relatively stationary bag holding device arranged in operative position to said chute for supporting a bag in substantial alinement with the chute, and to be displaced upon rotation of the chute in one 15 direction, means for extending the chute to thereby project one end of the chute into the bag alined therewith for initially engaging the chute with the bag, coin controlled means for rotating the chute subsequent to the extension 20 thereof for displacing the bag, a member mounted to rotate relative to the chute and insertable in the bag simultaneously with the insertion of said one end of the chute, and means in the path of the bag expanding member for causing the 25 same to swing relative to the chute upon swinging movement of the chute to thereby expand the bag, and a tray arranged to receive the expanded bag and the contents thereof.
4. In a device of the character described, and 30 in combination a revoluble charge emitting cylinder, a tray arranged to receive the discharge of said cylinder and including a pivoted section and a sliding section shiftable relative to the pivoted section, cams on the cylinder rotatable therewith, 35 means on the sliding tray section arranged in the path of the cams to cause a shifting of the sliding tray section relative to the pivoted section, means 40
- on the pivoted tray section engaged by the cams for rotating said pivoted section, and elastic means acting on said chute section in opposition to the action of said cams.
5. In a vending machine, a holder for paper bags open at its bottom, an extensible chute including a section pivoted at one end and a second section slidably engaged with the first named section and having an end arranged to be protruded into a bag within said holder, means normally retaining the second named section of the chute in a retracted position, means for projecting the second named chute section to cause said one end of the second named chute section to pass into the paper bag, and means for subsequently 80 rotating the first named chute section to thereby withdraw said bag from the holder through the open bottom of the latter.
6. In a vending machine, a longitudinally extensible chute pivoted at one end and having a free end adapted upon extension of said chute to be protruded into a paper bag, a bag opening member pivotally carried by said chute and normally lying in a plane parallel to said chute, and being also adapted for introduction into the bag 85 upon projection of said end of the chute into the bag, a bag clamping member swingable relative to said chute and coacting with the free end of the chute to clamp the bag thereon, means for rotating said chute, means for rotating said bag opening member upon downward movement of said chute, for expanding the bag, and additional means for swinging said bag clamping member to a releasing position relative to the chute when said chute begins its upward movement.
